WITNESS:

UNITED STATES PATENT OFFICE.

JOHN DWORNICZAK, OF CHESTER, PENNSYLVANIA.

BRUSH.

1,391,882.

Specification of Letters Patent. Patented Sept. 27, 1921.

Application filed June 18, 1920. Serial No. 389,931.

To all whom it may concern:

Be it known that I, JOHN DWORNICZAK, a citizen of Republic of Poland, residing at Chester, in the county of Delaware and 5 State of Pennsylvania, have invented new and useful Improvements in Brushes, of which the following is a specification.

The invention relates to brushing and scrubbing and has for an object to provide a 10 brush for cleaning or polishing purposes.

The invention comprehends among other features a brush which is preferably motor driven and which may be constructed to provide a suitable head having bristles, the head 15 being removable from the body for the purpose of replacing a worn out brush with a new one.

In the further disclosure of the invention reference is to be had to the accompanying 20 drawings constituting a part of this specification, in which similar characters of reference denote corresponding parts in all the views, and in which,—

Figure 1 is an elevation of the brush.

Fig. 2 is a fragmentary vertical sectional view taken through the brush head showing the manner of connecting the same to the shaft of the motor.

Fig. 3 is a view looking at the face of the 30 brush, and

Fig. 4 is a view looking at the face of the head.

Referring more particularly to the views the numeral 10 indicates an electric motor 35 having a suitable handle 11, the motor being adapted for connection with a suitable source of electric energy whereby the usual motor shaft 12 can be rapidly rotated. The shaft 12 has its projecting end 13 threaded 40 and furthermore includes an annular stop flange 14. The brush comprises the bristles 15 projecting from the brush head 16, which is preferably a two-part construction, consisting of the sections 17 and 18, the former 45 carrying the bristles 15. The section 18 is in the nature of a cover and is provided centrally with a squared opening 19, the section being suitably fitted into a counter-sunk recess 20 in the section 17, which also 50 has a squared opening 21 alining with the opening 19.

A coupling plate 22 is provided, the same having a squared head 23 fitting the squared openings 19, 21, and through which plate

22 pass suitable screws 25 extending through 55 the sections 17, 18, to secure the coupling to the brush body, the squared head 23 having a threaded central bore 24 receiving the threaded end 13 of the motor shaft 12 with the coupling adapted to bear against the 60 flange 14 so as to limit the screwing of the coupling onto the threaded part of the motor shaft.

From the foregoing description it will be seen that when the bristles 15 of the brush 65 wear out the brush in its entirety can be removed from the motor shaft and then by removing the screws 25, the coupling and section 18 can be removed to provide access to the bristles where they are fixed into 70 the part 17, the screws 25 serving to secure the coupling to the brush body and also securing the section 18 to the section 17. It will be noted that the brush in its entirety comprises substantially the connectible sections 17, 18, together with the bristles 15 on the section 17, and also the coupling, and that as a unit in its make-up the brush structure can be applied to any desired form of 75 motor or other shaft provided it can be suitably attached or threaded thereto. 80

Having described my invention, I claim—

The combination with a rotatable shaft 85 having a threaded end, of a brush including two disk-like members of relatively different thicknesses, both of said members having alined squared openings, one of said members having a plurality of apertures, bristles threaded through the apertures and projecting from one side of the member, the opposite side or face of said member being recessed and providing an annular shoulder, the other part of said head reposing upon 90 said shoulder, a flange projecting from the confronting face of the latter mentioned member inwardly of the peripheral edge, and arranged to engage said shoulder, a coupling plate reposing upon the latter mentioned member, fastening elements passed through said plate and the respective parts 95 of the head of the brush, whereby all of said parts are held operatively associated, a threaded boss projecting centrally from said plate and received by the aforementioned squared openings, and said boss being 100 threaded on the threaded end of the shaft. 105

In testimony whereof I affix my signature.
JOHN DWORNICZAK.
